CLAIM

The ornamental design for a note and clip, as shown and described.

DESCRIPTION

FIG. 1 shows a perspective view of a first embodiment of a design of a note and clip.
 FIG. 2 shows the right-side view of FIG. 1. A left-side view is a mirror image of the right-side view.
 FIG. 3 shows another perspective view of FIG. 1.
 FIG. 4 shows a front view of FIG. 1. A back view is a mirror image of the front view.
 FIG. 5 shows a right-side view of FIG. 1. A left-side view is a mirror image of the right-side view.
 FIG. 6 shows a back view of FIG. 1. A front view is a mirror image of the back view.
 FIG. 7 shows a top view of FIG. 1.
 FIG. 8 shows a bottom view of FIG. 1.
 FIG. 9 shows another perspective view of FIG. 1.
 FIG. 10 shows a front view of FIG. 1. A back view of this embodiment is a mirror image of the front view.
 FIG. 11 shows a right-side view of FIG. 1. A left-side view of this embodiment is a mirror image of the right-side view.
 FIG. 12 shows a perspective view of a second embodiment of design of a note and clip.
 FIG. 13 shows a right-side view of FIG. 12. A left-side view of this embodiment is a mirror image of the right-side view.
 FIG. 14 shows another perspective view of FIG. 12.

FIG. 15 shows a front view of FIG. 12.

FIG. 16 shows a right-side view of FIG. 12. A left-side view of this embodiment is a mirror image of the right-side view.
 FIG. 17 shows a back view of FIG. 12. A front view of this embodiment is a mirror image of the back view.

FIG. 18 shows a top view of FIG. 12.

FIG. 19 shows a bottom view of FIG. 12.

FIG. 20 shows another perspective view of FIG. 12.

FIG. 21 shows a front view of FIG. 12. A back view of this embodiment is a mirror image of the front view.

FIG. 22 shows a right-side view of FIG. 12. A left-side view of this embodiment is a mirror image of the right-side view.
 FIG. 23 shows a perspective view of a third embodiment of a design of a note and clip.FIG. 24 shows a right-side view of FIG. 23. A left-side view of this embodiment is a mirror image of the right-side view.
 FIG. 25 shows another perspective view of FIG. 23.

FIG. 26 shows a front view of FIG. 23. A back view of this embodiment is a mirror image of the front view.

FIG. 27 shows a right-side view of FIG. 23. A left-side view of this embodiment is a mirror image of the right-side view.
 FIG. 28 shows a back view of FIG. 23. A front view of this embodiment is a mirror image of the back view.

FIG. 29 shows a top view of FIG. 23.

FIG. 30 shows a bottom view of FIG. 23.

FIG. 31 shows another perspective view of FIG. 23.

FIG. 32 shows a front view of FIG. 23. A back view of this embodiment is a mirror image of the front view.

FIG. 33 shows a right-side view of FIG. 23. A left-side view of this embodiment is a mirror image of the right-side view.
 FIG. 34 shows a perspective view of a fourth embodiment of a design of a note and clip.FIG. 35 shows a right-side view of FIG. 34. A left-side view of this embodiment is a mirror image of the left-side view.
 FIG. 36 shows another perspective view of FIG. 34.

FIG. 37 shows a front view of FIG. 34. A back view of this embodiment is a mirror image of the front view.

FIG. 38 shows a right-side view of FIG. 34. A left-side view of this embodiment is a mirror image of the right-side view.
 FIG. 39 shows a front view of FIG. 34. A back view of this embodiment is a mirror image of the front view.

FIG. 40 shows a top view of FIG. 34.

FIG. 41 shows a bottom view of FIG. 34.

FIG. 42 shows another perspective view of FIG. 34.

FIG. 43 shows a front view of FIG. 34. A back view of this embodiment is a mirror image of the front view.

FIG. 44 shows a right-side view of FIG. 34. A left-side view of this embodiment is a mirror image of the right-side view.
 FIG. 45 shows a perspective view of a fifth embodiment of a design of a note and clip.FIG. 46 shows a right-side view of FIG. 45. A left-side view of this embodiment is a mirror image of the right-side view.
 FIG. 47 shows another perspective view of FIG. 45.

FIG. 48 shows a front view of FIG. 45. A back view of this embodiment is a mirror image of the front view.

FIG. 49 shows a right-side view of FIG. 45. A left-side view of this embodiment is a mirror image of the right-side view.
 FIG. 50 shows a front view of FIG. 45. A back view of this embodiment is a mirror image of the front view.

FIG. 51 shows a top view of FIG. 45.

FIG. 52 shows a bottom view of FIG. 45.

FIG. 53 shows another perspective view of FIG. 45.

FIG. 54 shows a front view of FIG. 45. A back view of this embodiment is a mirror image of the front view.

FIG. 55 shows a right-side view of FIG. 45. A left-side view of this embodiment is a mirror image of the right-side view. FIG. 56 shows a perspective view of a sixth embodiment of a design of a note and clip.

FIG. 57 shows a right-side view of FIG. 56. A left-side view of this embodiment is a mirror image of the right-side view. FIG. 58 shows another perspective view of FIG. 56.

FIG. 59 shows a front view of FIG. 56. A back view of this embodiment is a mirror image of the front view.

FIG. 60 shows a right-side view of FIG. 56. A left-side view of this embodiment is a mirror image of the right-side view. FIG. 61 shows a front view of FIG. 56. A back view of this embodiment is a mirror image of the front view.

FIG. 62 shows a top view of FIG. 56.

FIG. 63 shows a bottom view of FIG. 56.

FIG. 64 shows another perspective view of FIG. 56.

FIG. 65 shows a front view of FIG. 56. A back view of this embodiment is a mirror image of the front view; and, FIG. 66 shows a right-side view of the FIG. 56. A left-side view of this embodiment is a mirror image of the right-side view.

The surfaces of the note are entirely unclaimed except for the edge lines and the central vertical line that are shown as solid lines. The broken-line features in the figures are for illustrative purposes only and form no part of the claimed design.
